UNITED STATES PATENT OFFICE.

IKE SCHLESINGER, OF EAST ORANGE, NEW JERSEY.

DESIGN FOR A KNITTED CAP.

Application filed January 14, 1922. Serial No. 203. Term of patent 3½ years.

To all whom it may concern:

Be it known that I, IKE SCHLESINGER, a citizen of the United States, residing at East Orange, county of Essex, and State of New Jersey, have invented a new, original, and ornamental Design for Knitted Caps, of which the following is a specification, reference being had to the accompanying drawing, forming part thereof.

I claim:

The ornamental design for a knitted cap, as shown.

IKE SCHLESINGER.
